(57) **CLAIM**

The ornamental design for an underwear for women, as
shown and described.

DESCRIPTION

FIG. 1 is a perspective view of an underwear for women
showing in my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view of the underwear for women as shown
in a position of use.

The broken line outline of the partial human figure in FIG.
8 assists in illustrating how the claimed design may appear
when in a position of use, but forms no part of the claimed
design.
